JAMES T. DOWDALL
By His Attorney
Herman Bloch

UNITED STATES PATENT OFFICE.

JAMES T. DOWDALL, OF GLEN MORRIS, NEW YORK.

SPOOL SUPPORT.

Application filed January 10, 1923. Serial No. 611,706.

To all whom it may concern:

Be it known that I, JAMES T. DOWDALL, a citizen of the United States of America, residing at Glen Morris, Queens County, State of New York, have invented certain new and useful Improvements in Spool Supports, of which the following is a specification.

This invention relates to spool holders and in particular to one which is adapted to be used in connection with the heavier type of sewing machine, although the device is readily adapted to any machine using thread, twine or wire off a spool.

15 A particular object of my invention is to do away with a wasteful fault common in practically all devices at present in use with power machines, that is, when the thread or wire is drawn from a spool, which is centered on a revolvable spindle, the thread or wire, if it is not drawn off tautly will drop down in loose circlets about the lower end of the spool and the spindle as it revolves, will tangle the loose thread or wire and the operator in order to clear the tangled thread from about the spindle will pull off a bunch of the thread and discard it. This waste in a large manufacturing establishment quickly assumes large proportions.

20 Another object of my invention is to provide a spindle which will not only grip and hold the spool to prevent it from tending to creep upwardly off the spindle but will also hold the spool vertically so that the thread or wire may be drawn off with a minimum of friction, and therefore less liability of breakage.

25 Referring to the drawing, forming part of my application, in which one embodiment of my invention is disclosed,

Fig. 1 is a view in elevation of my spool holder, parts thereof being shown in section to make illustration more clear;

30 Fig. 2 is a side view of the device as shown in Fig. 1;

Fig. 3 is a view in elevation showing the adaptation of my spool holder to a cone, upon which the lighter kind of thread is wound in larger quantities; and

35 Fig. 4 is a sectional view taken on line 4—4 of Fig. 1 of the brush and holder, showing how the former is maintained against the spool when a quantity of the thread has been removed.

40 Referring to the drawing in detail, 10 denotes in general the spool holder which con-

sists of a vertically disposed post 11 from which extends the offset upright arm 12. The post 11 is retained in some suitable part 13 of a machine through the medium of a set screw 14, and the upper end of said post enters the bore 15 of a saddle block 16 which pivotally holds the spool gripping fingers 17 and 18.

These spool gripping fingers 17 and 18 are bent intermediate their ends so that the upper ends will form tongs which tend to open, due to a coiled retractile spring 19 fastened to, and extending between the lower ends of said fingers 17 and 18. The fingers 17 and 18 are pivoted in the upper slotted portion of the saddle 16 through the medium of driven pins 20 adjacent their bent portions. The inner sides of the upper portions of the fingers 17 and 18 are flattened so that when they are squeezed together they will pass into the bore 21 of a spool of thread, and against the action of the spring 19 will expand against the inner wall of the spool bore 21 to hold the spool 22 firmly in place.

45 In order to maintain the spool in vertical position, it is necessary to provide for the closing of the finger ends simultaneously and in order to accomplish this, I provide a centering pin 23 which is curved to allow 50 of movements of both the fingers 17 and 18. The pin 23 is properly peened to prevent its working out of position and getting lost. This pin, it will be noted upon reference to Fig. 1, will only allow the fingers 17 and 18 to close equally so that both will have to be moved at once. If only finger 17 was moved,

the tendency of that finger would be to throw the end of the pin 23 in finger 18 downwardly, thus preventing movement of 55 the finger 17, due to the jamming of the pin in finger 18. The fingers come together always on the median line of the saddle block 16.

60 When the thread or wire is unwound from the spool, the adjacent strands to the one being drawn off usually fall down, and off the end of the spool to eventually become tangled in the holder. In order to prevent this, I provide a flat brush element 24 which 65 is soldered or otherwise attached to an adjustable sleeve 25 which can slide freely up and down the arm 12 and which may be held in any desired position thereon by a wing-nut 26 which is carried in the sleeve 25 and 70 which engages the arm 12. In order to keep the brush against the spool when the thread

is partly drawn off, I provide a spring 25^a, one end of which is attached to sleeve 25 and the free end of which presses against the brush, which may be pivoted as at 24^a 5 to sleeve 25. The brush may be of ordinary stiff hair bristles, or in the case of a spool of wire may be of stiff wire, and in rubbing against the spool prevents the loose thread or wire from dropping off the spool to subsequently become tangled and wasted. The 10 brush may be of any width desired, and the pressure of the bristles against the spool is regulated by the wing nut 26.

It is apparent that my holder is equally 15 adaptable for use with the cones and spools common in knitting mills and by bending the upper end of the arm 12 to extend over the cone and forming an eye 27 in the end thereof, through which the thread passes, 20 I provide a means whereby the thread will be supported from above and will therefore not tend to become loose and fall down below the bottom of the cone where it will catch and cause breakage. However, in 25 cases where hardened or wire thread is used on the cones which tend to curl or tangle, my brush device is applied as shown.

What I claim is:—

1. In a device of the character described, 30 a vertically disposed post member, a pair of gripping members pivotally associated with said post member and adapted to hold a spool, an arm projecting from said post and extending parallel to said gripping members, and means on said arm for engaging the periphery of said spool to prevent the dropping off of thread strands from said spool.

2. In a device of the character described, 40 a saddle block, a pair of arms pivoted in said saddle block, and means passing through said arms to cause the ends of the same when brought together, to close on the median line of said saddle block.

45 3. A spool holder comprising a post member, a saddle block revolvably mounted on said member, spool holding arms on said saddle block, and means mounted remote from said spool-holding arms and adapted 50 to engage a spool held by said arms whereby loose strands of thread will be prevented from dropping off said spool.

4. A spool holder comprising a support

adapted to be attached to a machine part, a saddle revolvably mounted on said support, 55 a pair of gripping members pivotally associated with said saddle, a spool carried by said gripping members and adapted to revolve therewith when the contents of said spool are drawn off, and means adapted to engage the outer strands of material on said spool whereby the same will be prevented from dropping off of said spool.

5. A spool holder comprising a support, 60 a saddle revolvably mounted on said support, a pair of tong members pivoted in said saddle, a spring member connecting the lower extremities of said tong members whereby the upper ends thereof will tend to separate, a spool adapted to slip over the upper ends 70 of the tongs, and means associated with said tong members whereby the same will be caused, when closed, to support the spool in the median line of said saddle.

6. A spool holder comprising a support, 75 a spool of material held thereon, an upwardly extending arm associated with and parallel to said support, and means adjustably associated with the arm with which the material being drawn off is adapted to contact, whereby tangling of the material on the spool is prevented.

7. A spool holder, comprising a support, 80 adapted to receive a spool, a rod associated with said support and adjacent thereto, a wiper element slidable on said rod, and means for releasably securing said wiper element in adjusted position longitudinally of said rod.

8. The combination of a spool support and 85 a wiper support, said wiper support extending longitudinally of the spool support and having a wiper element associated therewith, and means for releasably securing said wiper element in adjusted position longitudinally of said spool support.

9. In combination, a spool support and means for adjustably mounting a wiper element comprising a support for a wiper holder associated with said spool support, a wiper holder slidably associated with said wiper holder support, and means for releasably securing said wiper holder in adjusted position longitudinally of said spool support.

JAMES T. DOWDALL.
